Primary Examiner — Ruth McInroy*(74) Attorney, Agent, or Firm* — Volpe and Koenig, P.C.(57) **CLAIM**

The ornamental design for a protective mask, as shown and described.

DESCRIPTION

FIG. 1 is a front and left-side perspective view of a protective mask showing our new design;

FIG. 2 is a front elevational view thereof;

FIG. 3 is a right side elevational view thereof, the left side being a mirror image;

FIG. 4 is a top plan view thereof; and,

FIG. 5 is a bottom plan view thereof.

All broken-lines appearing in the drawings form no part of the claimed design.
